(57) **CLAIM**

The ornamental design for a tubular container, as shown.

DESCRIPTION

FIG. 1 is a front view of a tubular container showing my new design;

FIG. 2 is a top view thereof;

FIG. 3 is a bottom view thereof;

FIG. 4 is a side view thereof;

FIG. 5 is a perspective view thereof;

FIG. 6 is a front view thereof, shown in use; and,

FIG. 7 is a perspective view thereof, shown in use.

The broken lines illustrate portions of the tubular container that do not form a part of the claimed design.
